His Attorney.

UNITED STATES PATENT OFFICE.

JOHN REECE, OF ST. LOUIS, MISSOURI, ASSIGNOR TO EVR KLEAN SEAT PAD CO., OF ST. LOUIS, MISSOURI, A CORPORATION OF MISSOURI.

SEAT COVER.

Application filed March 10, 1922. Serial No. 542,590.

To all whom it may concern:

Be it known that I, JOHN REECE, a citizen of the United States, residing at St. Louis, Missouri, have invented a new and useful Seat Cover, of which the following is a specification.

This invention relates to seat covers.

An object of the invention is to provide an improved removable and interchangeable seat cover comprising seat and back members having their adjacent edges pivotally united near their outer edges, leaving the intermediate portions of said members disconnected in order to enable either or both of said members to bend and conform to the curvature of the seat or support on which the cover is placed, each of said members including a body portion of sufficient flexibility to permit bending to obtain proper adjustment to the curvature of the seat and of sufficient stiffness so that either member will remain extended vertically.

Another object of the invention is to provide an improved seat cover including seat and back members characterized as stated, in combination with a novel form of hinge device uniting the two members adjacent to their lateral edges to permit the members to conform properly to the curvature of the seat.

Other objects will appear from the following description, reference being made to the drawing in which—

Fig. 1 is a view showing one of the sides of the seat cover with the two members thereof extended.

Fig. 2 is a similar view showing the opposite side of the seat cover.

Fig. 3 is a sectional view on the line 3—3 of Fig. 2.

Fig. 4 is an enlarged plan view of one of the hinge devices.

In the preferred embodiment of the invention shown my improved seat cover comprises separate members 1 and 2 of porous material, such as straw matting. Said members 1 and 2 are characterized by sufficient flexibility to bend readily to the contour and shape of the seat or support upon which they may be used, and one or both thereof being characterized by sufficient stiffness so that it will remain in raised position against the back of a seat or support without folding or crumpling upon itself.

The straw matting, or other appropriate material that may be chosen for use, is made or cut to proper size so that one may be used as a seat member and the other as a back member.

A relatively wide marginal reinforcement 3 of cloth or other substantially non-elastic material is secured to each of the members 1 and 2, said reinforcements 3 being on the same side of said members and having their inner edges tucked under and secured by lines of stitching 4. Additional strength may be obtained, as shown, by two centrally disposed non-elastic strips 5 extending transversely across each member of the seat cover and secured thereto by lines of stitching 6. However, it is not necessary to employ these transverse reinforcements unless desired, although they really do afford additional strength without impairing the other desirable qualities of the article. The ends of the strips 6 overlap the marginal reinforcements 3 and the lines of stitching 6 pass through the reinforcements 3 and the matting.

A narrow marginal reinforcement 7 of non-elastic material is folded to enclose the entire marginal edge of each member of the cover including also the outer edges of the strips, while the edge of each member that is adjacent to the other member is enclosed by a separate narrow marginal reinforcement 7^a. A line of stitching 8 passing through the folded edge of the reinforcements 7 and 7^a and through the interposed portions of the wide non-elastic strips 3 securely hold the reinforcements 7 and 7^a on the edges of the members of the seat cover. The wide strips 3 afford anchorage for the lines of stitching 8 preventing the reinforcements 7 and 7^a from tearing off.

The reinforcements 7 also extend across from one member of the cover to the other constituting hinges at the side edges of said members, permitting the members to fold over one upon the other in either direction. If desired additional hinge strips 9 of cloth or other flexible non-elastic material may be employed. Such additional hinge strips are illustrated in Figs. 2, 3 and 4 but are not on the device shown in Fig. 1, the reinforcement 7 on the device shown in Fig. 1 forming pivotal connections uniting the seat and back members near their lateral edges, leav-

ing the intermediate central portion of said members disconnected so that they may curve away from each other. As shown, the hinges 9 are composed of narrow strips 5 of cloth having their edges tucked under said strips being secured in position by rows of stitching 10 running from end to end of each strip and beyond.

The hinge or pivotal connections for the 10 members 1 and 2 are designed and intended to permit said members to be folded flat one upon the other in either direction, and also to permit the intermediate portions of the members to bend or curve away from each 15 other as required to conform to the curvature of the back of a seat or of the bottom of a seat without exerting too much strain or force upon the other member. This is a highly desirable construction and arrangement as it adapts the cover for use upon seats having flat seating and back portions, as well as upon seats having either portion curved.

From the foregoing it is obvious that my 25 invention adequately obtains all of its intended objects and advantages. It is not so restricted that any specific material must be used to form the seat and back members but it is important that said members shall be characterized as mentioned so 30 as to adapt the cover for use upon seats of every construction and form.

I do not restrict myself unessentially, but what I claim and desire to secure by Letters 35 Patent is:—

1. As an article of manufacture, a seat cover comprising a seating member and a back member, of which the back member is characterized by sufficient stiffness to remain 40 extended vertically and both of which are characterized by sufficient flexibility to permit bending to the curvature of the seat and back of the support to which they may be applied, and a border of flexible material 45 enclosing the outer marginal edges of each of said members, and pivotally uniting the lateral side edges of said members and leaving the intermediate portions of said members disconnected to permit the intermediate portions to spread away from each other in conforming to the contour of the seat and back of the support.

2. As an article of manufacture, a seat cover comprising a seating member and a back member, each of which is characterized by sufficient stiffness to remain extended vertically and by sufficient flexibility to permit bending to the curvature of the seat and back of the support to which the cover 55 may be applied, a border of flexible material enclosing the marginal edges of each of said members and extending across from one member to the other, and pivotally uniting said members at their outer edges and permitting the intermediate portions to

spread away from each other in conforming to the contour of the seat and back of the support.

3. As an article of manufacture, a seat cover comprising a seating member and a back member, each of which is characterized by sufficient stiffness to remain extended vertically and by sufficient flexibility to permit bending to the curvature of the seat and back of the support to which the cover 75 may be applied, a border of flexible material enclosing the marginal edges of each of said members and extending across from one member to the other, and pivotally uniting said members at their outer edges, the 80 central portions of said members being disconnected to permit them to spread apart and curve away from each other in conforming to the contour of the seat and back of the support.

4. As an article of manufacture, a seat cover comprising a seating member and a back member, each of which is characterized by sufficient stiffness to remain extended vertically and by sufficient flexibility to permit bending to the curvature of the seat and back of the support to which the cover may be applied, a border of flexible material enclosing the marginal edges of each of said members and extending across from one member to the other, and pivotally uniting said members at their outer edges, and transverse strips of non-elastic material secured to each of said members and permitting the intermediate portions to spread 90 away from each other in conforming to the contour of the seat and back of the support.

5. As an article of manufacture, a seat cover comprising a seating member and a back member, each of which is composed of straw matting and each being characterized by sufficient stiffness to remain extended vertically and by sufficient flexibility to permit bending to the curvature of the seat and back of the support to which the cover may be applied, a relatively wide strip of non-elastic flexible material secured to the marginal portion of each of the said members, a relatively narrow marginal reinforcement 105 enclosing the marginal edge of each of said members and secured thereto and to said wide reinforcements by stitching, and hinge connections uniting said members near their lateral edges leaving the intermediate central portion of said members disconnected so that they may curve away from each other in conforming to the contour of the seat and back of the support.

6. As an article of manufacture, a seat cover comprising a seating member and a back member, each of which is composed of straw matting and each being characterized by sufficient stiffness to remain extended vertically and by sufficient flexibility to permit bending to the curvature of the seat and back of the support.

back of the support to which the cover may be applied, a relatively wide strip of non-elastic flexible material secured to the marginal portion of each of the said members, 5 a relatively narrow marginal reinforcement enclosing the marginal edge of each of said members and secured thereto and to said wide reinforcements by stitching, pivotal connections uniting said members near their 10 lateral edges leaving the intermediate central portion of said members disconnected so that they may curve away from each other in conforming to the contour of the seat and the back of the support, and intersecting reinforcing strips of non-elastic material 15 crossing each of said members and secured thereto by stitching.

7. A seat cover comprising a seat member made of woven fabric, a marginal reinforcement surrounding and embracing the margins of said seat member, a back member made of woven fabric, a marginal reinforcement surrounding and embracing the margins of said back member, one of said members being provided with an intermediate reinforcing strip extending from one of its marginal reinforcements to another and secured to the woven fabric, and hinges uniting said seat and back members.

8. A seat cover comprising a seat member made of matting, a marginal reinforcement surrounding and embracing the margins of said seat member to enclose the margins of the matting, stitches whereby said reinforcement is secured to the matting, a back member made of matting, a marginal reinforcement surrounding and embracing the margins of said back member, stitches whereby

the last mentioned reinforcement is secured to said back member, an intermediate reinforcing strip extending across the bottom face of said seat member and secured to the marginal reinforcement at opposite margins thereof, an intermediate reinforcing strip 40 extending across the rear face of said back member and secured to the marginal reinforcement at opposite margins thereof, and hinges uniting said seat and back members.

9. A seat cover, comprising a flexible seat member, a marginal reinforcement embracing and secured to the outside edges of said seat member, a flexible back member, a marginal reinforcement embracing and secured to the outside edges of said back member, and hinges uniting said seat and back members 50 near their lateral edges and permitting the intermediate portions of said members to spread away from each other in conforming to the seat and back of the support to which the seat cover is applied.

10. A reversible and flexible garment protector for seats, comprising a seat back section and a seat section formed of straw matting adapted to be folded against each other, the adjacent edges of said sections being 55 spaced apart and unattached, a flexible binding strip secured to three sides of each of said sections for flexibly connecting the same together at their sides only, so that the intermediate portion of the adjacent edge of each section may be conformed to either the seat or back without putting undue strain on the sections, thereby eliminating the danger of tearing.

JOHN REECE.
